CLAIM

The ornamental design for a makeup bag, as shown and described.

DESCRIPTION

FIG. 1 is a front-left-top perspective view of a makeup bag in a closed position showing the new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a rear elevation view thereof;

FIG. 7 is a front elevation view thereof;

FIG. 8 is a bottom plan view of the makeup bag of FIG. 1 in an open position, shown with the top strap removed;

FIG. 9 is a perspective view thereof, shown with the top strap removed; and,

FIG. 10 is a rear side elevation view thereof.

The broken lines in the figures depict portions of the makeup bag that form no part of the claimed design.
